UNITED STATES PATENT OFFICE.

JAMES R. McGEE, OF MILWAUKEE, WISCONSIN.

AUTOMATIC ELEVATOR-DOOR.

1,343,328.

Specification of Letters Patent. Patented June 15, 1920.

Application filed September 16, 1919. Serial No. 324,210.

To all whom it may concern:

Be it known that I, JAMES R. McGEE, a citizen of the United States, and resident of Milwaukee, in the county of Milwaukee and 5 State of Wisconsin, have invented certain new and useful Improvements in Automatic Elevator-Doors; and I do hereby declare that the following is a full, clear, and exact description thereof.

10 My invention relates to new and useful improvements in doors for the passage-openings of elevator shafts, and more particularly of that type adapted to be automatically opened and closed upon movement of 15 the elevator with respect to the opening.

It is in general the object of my invention to simplify and otherwise improve the structure, and to increase the efficiency and ease of operation of devices of this character.

20 It is further my object to provide an improved latch arrangement for locking the elevator door in closed position, which latch is releasable upon movement of the elevator theretoward in either direction.

25 A further object resides in the provision of an automatically operable door member movable in a vertical direction to and from its closing position, and provided with means for effecting detachable lever connection 30 with the elevator upon movement thereof adjacent the door whereby to effect opening or closing movement of the door.

With the above and other objects and advantages in view, which will be apparent as 35 the description proceeds, my invention resides in the novel features of construction, combination and arrangement of parts, which will be hereinafter more particularly described and defined by the appended 40 claims.

In the accompanying drawings:

Figure 1 is an elevational view of an automatic elevator door and operating mechanism constructed in accordance with my invention.

45 Fig. 2 is a transverse sectional view through the actuating lever and latch mechanism, the general plane of this section being indicated by the line 2-2 of Fig. 1.

50 Referring now more particularly to the accompanying drawings, 5 designates conventionally one of the floors of a building through which extends the shaft of an elevator A which, in the present structure, constitutes a primary actuating means for effecting opening and closing movements of a

door B associated with the entrance passage of the elevator shaft. This door is conventionally shown as comprising a slatted structure, and is slidably mounted in vertical 60 angle iron trackways 6 extending through and below the floor 5 whereby the door B may move below the floor to open the passage. For moving the door, upper links of a series of lazy tongs 7 are pivoted at horizontally spaced points 8 to the upper portion of the door, the lower links of the tongs being pivoted on a bolt 9 projecting from the front wall of the elevator shaft below the lower limit of movement of the door B. A 70 lever 10 is intermediately pivoted also on this bolt, and this lever is connected with the adjacent cross pivot of the series of lazy tongs by a link 11 whereby rocking movement of the lever will procure extension and 75 retraction of the lazy tongs to raise and lower the gate, it being noted that the horizontal spacing of the pivots 8 procures a two-point lifting action preventing possibility of binding engagement of the gate in 80 its tracks.

The gate is normally held in raised position by a latch bar 12 longitudinally carried by the lever 10 and slidable in guides 13 on said lever, a latch projection 14 extending 85 inwardly from the latch bar through a slot in the lever and being engageable in the recess of a keeper plate 15 mounted on the bolt 9 between the lever 10 and lazy tongs, said plate being also secured by lateral ears 16 90 to the front wall of the elevator shaft. The edge of the keeper plate is curved concentric with the axis of the lever 10 and the latch bar is yieldably urged to engage its projection in the recess of the keeper plate by a spring 95 17 coiled on the latch bar. Each end of the lever 10 is provided with divergent branches, and each end of the latch bar 12 is provided with correspondingly divergent branches which are offset laterally of the plane of the 100 latch bar, the latch bar branches 12^a which are disposed at the end of the lever lowermost when the gate B is closed being engageable against the branches of the lever there-adjacent. The latch bar branches 12^b at the 105 normally uppermost end of the lever are carried by an offset latch bar portion movable between the adjacent branches of the lever.

The elevator A carries a pair of abutment arms X and Y which are disposed below 110 the body of the elevator and which are engageable with the latch bar branches 12^b and

12^a respectively, the arm X being disposed a considerable distance below the arm Y, whereby said arms are spaced apart both longitudinally and transversely of the path 5 of movement of the elevator.

In Fig. 1, the various parts are shown in position immediately prior to opening the door B, upon downward movement of the elevator. In this operation, the abutment arm 10 X engages the uppermost latch bar branch 12^b and exerts a camming action to move said bar outwardly and thus retract the latch projection 14, permitting the door to drop to open position. As this takes place, 15 the other end of the lever is swung upwardly and as the elevator moves downwardly from the landing, the abutment arm Y will engage in the branches 12^a to swing the lever 10 in a reverse direction and raise the door 20 to closing position, the latch projection 14 moving into the recess of the latch plate 15 as the arm Y leaves the lever, to hold the door raised. Should the elevator move upwardly instead of downwardly from the floor 5, the abutment arm X would engage 25 the adjustment branch of the lever 10 to procure this same closing operation. When the elevator approaches the door mechanism from below, the abutment arm Y engages 30 the latch bar branches 12^a and first shifts the latch bar to retract the latch, then swings the latch bar and lever as the door is lowered. Upon continued upward movement, the 35 abutment arm X engages the latch bar branches 12^b to raise the door to closed position. I have thus provided a comparatively simple and exceedingly efficient mechanism for procuring proper opening and closing movements of the door of an elevator shaft automatically upon movement of the elevator toward or away therefrom in either direction. It is noted that the 40 branched ends of the latch bar 12 form shiftable portions of the lever unit.

45 While I have shown and described a preferred embodiment of my invention, it will be appreciated that various changes and modifications of structure may be employed to meet differing conditions of use and 50 manufacture, without departing in any manner from the scope of the appended claims.

What is claimed is:

1. A structure of the class described comprising a pair of trackways, a door slideable 55 with respect to said trackways, a set of lazy tongs having one end connected with said door, a stationary pivot for the other end of the tongs, a lever pivoted intermediate its ends on said stationary pivot and connected 60 with said lazy tongs, and primary actuating means movable into engagement with the opposite ends of said lever to successively

move the door from open to closed position and vice versa.

2. A structure of the class described comprising a pair of trackways, a door slideable with respect to said trackways, a set of lazy tongs having one end connected with said door, a stationary pivot for the other end of the tongs, a pivoted lever engageable by a 70 primary actuating member moving in the direction of movement of the door, said lever being connected with the lazy tongs, and latch means for holding said door against movement, said means being releasable incidental to engagement of a primary actuating member with the lever.

3. A structure of the class described comprising a pair of trackways, a door slideable with respect to said trackways, a set of lazy 80 tongs having one end connected with said door, a stationary pivot for the other end of the tongs, an intermediately pivoted lever connected with the lazy tongs, primary actuating means engageable with either end of 85 the lever, and latch means for holding said door against movement, said means being releasable incidental to engagement of the primary actuating means with either end of the lever.

4. A structure of the class described comprising a pair of trackways, a door slideable with respect to said trackways, a set of lazy tongs having one end connected with said door, a stationary pivot for the other end 95 of the tongs, an intermediately pivoted lever connected with the lazy tongs, primary actuating means engageable with either end of the lever, a latch bar slidably carried by said lever and engageable by the primary 100 actuating means at either end of the lever, and latch means operable by said latch bar.

5. An automatically operable door mechanism comprising a movable primary actuating means, a movable door, abutment arms carried by said primary actuating means, said arms being spaced both transversely and longitudinally of the path of movement of the primary actuating means, an intermediately pivoted lever connected with the door for movement thereof and having its end portions successively engageable by the abutment arms upon movement of the primary actuating means in a single direction, and latch means for holding said door against movement, said latch means being releasable incidental to engagement of either abutment arm with the lever.

In testimony that I claim the foregoing I have hereunto set my hand at Milwaukee, 120 in the county of Milwaukee and State of Wisconsin.

JAMES R. McGEE.
